UNITED STATES PATENT OFFICE.

WILLIAM G. FORCIER, OF WOLLASTON, MASSACHUSETTS.

VENTILATING SYSTEM.

1,348,557.

Specification of Letters Patent.

Patented Aug. 3, 1920.

Application filed July 31, 1919. Serial No. 314,405.

To all whom it may concern:

Be it known that I, WILLIAM G. FORCIER, a citizen of the United States, residing at Wollaston, in the county of Norfolk and

5 State of Massachusetts, have invented certain new and useful Improvements in Ventilating Systems, of which the following is a specification.

The object of this invention is to so construct a building that the cost of construction will be minimized and the proper heating and ventilating thereof will be facilitated. The invention seeks to provide means whereby a supply of fresh air may be admitted to the rooms of a building and the desired temperature of the rooms maintained in cold weather with an economical consumption of fuel.

20 The invention is illustrated in the accompanying drawings and will be hereinafter fully described, the novel features being subsequently particularly pointed out in the appended claims.

In the drawings—

25 Figure 1 is a vertical section of a portion of a building constructed in accordance with my invention;

30 Fig. 2 is a detail elevation of means provided for effecting a circulation of outside air within the wall of the building;

Fig. 3 is an elevation of one form of ventilator employed in the practice of the invention;

35 Fig. 4 is a detail section of a portion of the ventilator shown in Fig. 3;

Fig. 5 is a longitudinal section of said ventilator;

Fig. 6 is a detail perspective view of the operating mechanism for said ventilator.

40 In carrying out my invention, I employ a foundation 1 which may be of any well-known type but will preferably be of concrete and upon the said foundation I place

45 for the first story of the building being supported on said joists. Girders 5 are placed upon the sills 2 and it will be understood, of course, that the four walls of the building are identical in construction although only

50 one wall is shown in the drawing. The sills 2 and girders 6, supported by the usual studding rising from the sills, will preferably be of lumber and to the outer faces of the sills and the girders as well as the beams and

55 girders supporting the roof, I secure a cardboard sheathing 7 which extends the full

height of the building. The joints between the cardboard sheathing and the several sills and girders may be made air-tight in any desired manner as, for instance, by calking 60 the same with felt. Spacers or straps 8 are secured to the cardboard sheathing at intervals and serve to hold the same against the several sills and girders and to the outer

sides of the said spacers I secure the outer 65 sheathing 9 which will preferably be of lumber but may be of any other material now generally employed. The lumber sheathing 9 is shown with clapboarding 10 secured upon its outer face so as to impart an attrac-

70 tive finish to the building, but any other desired finish may be applied, as brick veneer, shingles, or stucco. The roof, indicated conventionally at 11, extends over the upper end of the space 12 between the sheathings 7 and

75 9 but the lower end of the said space is left open although it is covered by a screen 13 to prevent the entrance of insects. At the corners of the building, studding or corner posts will, of course, be employed and simi-

80 lar elements will be provided at the door and window openings and secured in place in the same manner as such elements are now generally fitted. Spaced inwardly from the sheathing 7 is a partition 14 which will be

85 constructed of plaster so that it may be fitted air-tight against the several girders or other devices interposed in the wall for supporting the floors or other building elements as well as for the ventilating members which

90 are extended through the wall as will presently appear, a dead air space 15 being thus provided between the sheathing 7 and the wall 14. Spaced inwardly from the parti-

95 tion or intermediate wall 14 is an inner wall 16 which is similar in construction to the partition 14 and forms the sides of the outer rooms, the ceiling 17 extending between the opposed inner walls 16 in the usual manner.

A second dead air space 18 will obviously be 100 formed between the walls or partitions 14 and 16 and these dead air spaces serve effectually counteract the tendency of buildings to accumulate dampness and will also tend to keep the temperature within the

105 building uniform through all weather conditions so that in severe cold weather the building may be effectually heated with a small amount of fuel.

To permit circulation of air through the 110 air space 12, I provide in the outer wall or sheathing 9 near the roof an opening 19

which is covered by a screen 20 to prevent the entrance of insects and around the said opening is provided a hood 21 to protect the parts against weather elements. The 5 opening 19 may be covered at will by a damper 22 slidably mounted in cleats or other guides 23 secured upon the inner face of the sheathing 9, said damper being provided with an opening 24 corresponding in 10 form and size with the opening 19. At the ends of the damper 22 are brackets 25 to which are secured the ends of short cables 26 which cables extend over and are secured to quadrants 27 mounted for rocking movement at the opposite sides or ends of the damper. The quadrants may be pivoted upon the sheathing, but I have illustrated a support consisting of a bearing sleeve 28 secured through the sheathing 7 and the 15 walls 14 and 16 in which the shaft 29 of a quadrant is journaled, this construction providing a more extended support for the quadrant and thereby more firmly holding it in its operative position. Upon each 20 quadrant is an arm 30 to the free end of which is pivoted a link 31, the lower end of which is pivoted to an operating lever 32 fulcrumed in the wall 14 and extending through the sheathing 7 and the walls 14 25 and 16. The inner end of the lever 32 is hollow or provided with a socket 33 in which may be engaged a handle 34 to rock the lever when it is desired to adjust the damper, and the slots or openings 35 in which the 30 said lever plays may be lined with felt or similar material so that leakage of air through the same will not occur. If the damper 22 be set in the position shown in Fig. 2 the opening 19 will be covered and 35 there will be no circulation through the space 12 except such as may be due to the escape of air from the building. If, however, it be desired to permit a circulation of air through said space, a handle 34 40 is inserted in the socket of the proper lever 32 and said lever is raised so as to pull through the link 31 upon the connected quadrant and thereby shift the damper 22 so as to bring the opening 24 thereof into 45 alignment with the opening 19 whereupon air will be permitted to enter the space 12 and flow down the same and carry off any moisture which may tend to collect therein. When the opening 19 is thus uncovered 50 accumulated hot air may escape so that the temperature of the building will be kept normal.

Within each room of the building, I provide an upper ventilator which is intended 55 to admit fresh air to the room and a lower ventilator which is intended to permit the escape of the vitiated air so that a circulation of air within the room will be set up and all impurities carried off. The ventilators each consists of a tubular casing 36 in-

serted through the sheathing 7 and the walls 14 and 16, the upper casing being also carried through the sheathing 9 so that it will be open to the atmosphere, while the lower casing opens through and terminates 70 at the inner sheathing 7. The casings may be covered with felt or otherwise calked in the openings through the sheathing 7 and the walls 14 and 16 so that leakage of air around the casings will not occur. The 75 lower casing is located at the floor of the room and extends through the base board 37 therein while the upper casing is located adjacent the ceiling and may be flush with the inner wall or provided with a flange fitting against the same. Within each casing is a plurality of vanes or blades 38 which are provided at their ends with trunnions or a shaft 39 journaled in the sides of the casing. If the member 39 be extended 80 through the blades, it will be pinned thereto, as indicated in Fig. 5. The pivot 39 of each blade will, of course, be disposed at the vertical center thereof and within the casing adjacent each blade are stops 40 which are arranged at opposite sides of the vertical planes of the respective blades so as to limit the movement thereof and they may be faced with felt or other material, so that a draft proof joint with the blades will be 85 effected as will be readily understood. The outer stops 40 terminate above the pivot pins of the respective blades, while the inner stops terminate below said points, as clearly shown in Fig. 5, and free movement 90 of the blades is thus permitted. Upon one end of the pivot for each blade is secured an arm 41 and the arms of the several blades are connected by a link 42 so as to effect simultaneous movement of the blades. One 95 of the arms 41 is equipped with a pin 43 which plays in a slot 44 in a tongue 45 depending from a sleeve 46 which is internally threaded and mounted upon a threaded rod or worm shaft 47 which is swiveled at its 100 outer end in a bracket 48 and equipped at its inner end with a hand wheel or pulley 49. The bracket 48 is secured rigidly to a partition 50 disposed longitudinally of the casing 36 and separating the operating 105 mechanism from the ventilator blades. The space between the partition and the casing at the inner ends thereof is sealed by a cover plate 51 which also provides the inner bearing for the worm shaft 47. The handle 49 110 at the lower ventilator will be in the form of a hand wheel, as shown, which may be easily grasped and manipulated but at the upper ventilator I substitute for the hand wheel a grooved pulley or disk 52 to which 115 is secured a cable or chain 53 having its ends depending from the said disk or pulley at opposite sides thereof and equipped with grips 54. The cable 53 will depend from the pulley to such point that its ends may 120

be easily reached by an occupant of the room and the ventilator, therefore, easily adjusted. The outer end of the upper casing 36 is covered by a screen 55 and a hood 56 is secured to the outer side of the building to extend over said screen and protect the same and the casing from the weather.

It will be noted that the lower ventilator opens into the space 12 which is open at its lower end to the atmosphere but the upper ventilator extends through said space and through the outer sheathing so that said upper ventilator is directly open to the atmosphere. Therefore, if the lower ventilator be opened the foul air contained in a room will escape but there will be no great rush of outside air into the room so that the foul air may be discharged without any substantial lowering of the temperature of the room. If the upper ventilator be opened atmospheric air will be admitted to the room so that the necessary supply of fresh air and oxygen may be easily obtained and if both ventilators be opened a circulation of air through the upper ventilator into the room and thence out through the lower ventilator will be created inasmuch as the upper ventilator is open to the outside air and furnishes direct access of the same to the room, while the lower ventilator communicates only indirectly with the outside air and it, therefore, counteracts the usual tendency of air to flow upwardly. Moreover, the upper end of the air space 12 is normally closed and the said space is normally a dead-air space in which there is no circulation. By employing the construction shown and described herein light materials may be employed and buildings quickly erected so that the cost of construction will be minimized and inasmuch as a plurality of dead-air spaces are provided around the building the

temperature of the same is more nearly uniform than with other known constructions and the cost of heating the building in cold weather will be very considerably reduced. A very efficient system of ventilation is provided which may be easily controlled by the occupant of the building without disarranging or rendering inoperative any of the parts.

Having thus described the invention, what is claimed as new is:

1. In building construction, a wall having an outer air space constantly open to the atmosphere at its lower end and normally closed at its upper end, a plurality of dead-air spaces at the inner side of the first-mentioned air space, and upper and lower ventilators in the wall, the upper ventilator extending through the first-mentioned air space and through all the dead-air spaces and the lower ventilator extending through the dead-air spaces and opening into the first-mentioned air space. 55

2. In building construction, a wall having an outer air space constantly open at its lower end to the atmosphere and normally closed at its upper end, and a plurality of dead-air spaces at the inner side of said outer air space, a ventilating casing extending through all said air spaces, and a hood at the outer end of said ventilator casing. 70

3. In building construction, a wall having an outer air space constantly open at its lower end to the atmosphere and normally closed at its upper end, and a plurality of dead-air spaces at the inner side of the said outer air space, and a ventilator extending through the dead-air spaces and opening 75 into the outer air space. 80

In testimony whereof I affix my signature.

WILLIAM G. FORCIER.
